UNITED STATES PATENT OFFICE.

GEORGE H. NEVIUS, OF SHREWSBURY, NEW JERSEY, ASSIGNOR TO E. I. DU PONT DE NEMOURS & COMPANY, OF WILMINGTON, DELAWARE, A CORPORATION OF DELAWARE.

DESIGN FOR A COMB.

Application filed April 26, 1923. Serial No. 5,944. Term of patent 7 years.

To all whom it may concern:

Be it known that I, GEORGE H. NEVIUS, a citizen of the United States, and a resident of Shrewsbury, in the county of Monmouth and State of New Jersey, have invented a certain new, original, and ornamental Design for a Comb, of which the following is a specification, reference being had to the accompanying drawing, forming part thereof.

In the drawing the figure is a front view of a comb, showing my new design.

I claim:

The ornamental design for a comb, as shown.

In testimony whereof I affix my signature.

GEORGE H. NEVIUS.
